UNITED STATES PATENT OFFICE.

HOWARD L. BEACH, OF MOUNT LEBANON, AND WILLARD J. FENDNER, OF PITTSBURGH, PENNSYLVANIA.

DUMP-CAR.

1,384,819.

Specification of Letters Patent. Patented July 19, 1921.

Application filed July 14, 1920. Serial No. 396,194.

To all whom it may concern:

Be it known that we, HOWARD L. BEACH and WILLARD J. FENDNER, citizens of the United States, and residents, respectively, 5 of Mount Lebanon and Pittsburgh, in the county of Allegheny and State of Pennsylvania, have made a new and useful Improvement in Dump-Cars, of which the following is a specification.

10 Our invention relates to railroad rolling stock and consists in a dump car of the type in which the car body is tilted on the car underframe to discharge its load to the side of the track.

15 The bodies of such cars have a pivoting or rocking mounting on the underframe which heretofore has been provided above the underframe bolsters and beneath the body floor. The immediate result of such a 20 mounting is to materially increase the distance between the body floor and the rail and to increase the height of the center of gravity. While this is unobjectionable in some classes of work and, at times, may even 25 be an advantage, there are many operations where this additional height is a serious disadvantage and one object of this invention is to provide an efficient lower mounting for a tilting body.

30 In a dump car of this type, it is usual to dump the body with air actuated cylinders and a common construction is to provide one or more cylinders on one side of the car for dumping the car in one direction and a 35 corresponding cylinder or cylinders on the other side for dumping the car in the opposite direction. An object of the present invention is to locate and connect all the cylinders and dumping mechanism so that they 40 will all coöperate in dumping the car in either direction.

The lowering of the car floor is especially 45 advantageous in a dumping flat car when used in road bed construction and maintenance of way as the section hands can shovel dirt and ballast onto the car more easily than if the floor was higher, and in the accompanying drawings disclosing our invention, we have illustrated such a car; 50 Figure 1 being side elevation of one end of the car; Fig. 2 is a vertical, transverse section on line 2—2 of Fig. 1 and illustrating the bolster and body mounting thereon, and

Fig. 3 being a similar section on line 3—3 of Fig. 1 and illustrating the operating 55 mechanism. Both cross sections show the body in one position in full lines and in another position in dot and dash lines.

The frame bolsters are mounted on the truck bolsters 1 and each comprises a portion of the underframe center sills 2, outwardly extending wing sections 3 and a tie-plate 4. Wing sections 3 are dish shaped and open upwardly and their bottom portions, adjacent truck bolster 1, provide a 60 track or rocker stand for rockers 5 upon which the body sills 6 are mounted. The latter carry the car floor, directly and thru suitable crossbearers 7.

Sills 2 and 6 are of the common fish-belly 70 type of girder which has proven so satisfactory in railway car construction. An essential feature of these sills is their substantial depth intermediate their comparatively shallow end portions. To retain the 75 advantages of these deep sills without detriment to the low mounting of the body rockers, we space sills 6 laterally of the body a greater distance from each other than the corresponding spacing of the under- 80 frame sills 2. The spacing of the latter is practically limited to the standard followed in car construction.

This arrangement permits the lower portion of the body sills to extend substantially 85 below the plane of the top of the underframe sills so that the depth of the body sills is not limited by the depth (or height) of the underframe sills or vice versa. This construction also provides a suitable space for 90 operating equipment as hereinafter mentioned.

It will be noted that when the body is upright, it is supported by the inner ends of both rockers 5 which, being separated by 95 the width of the center sill provides stability of the car, when traveling, by distributing the load to the underframe through spaced supporting points. When the body is tilted, it rocks on the rocker and the 100 bolster on the side to which it is tilted. Each wing 3 and its respective rocker 5 are provided with one or more interengaging lugs, here shown in the form of spur gear teeth 8 and 9 which mesh during the rocking 105 movement to prevent sliding of the rocker

on its stand. The teeth mesh with a rolling contact which eliminates friction between them. Each member 3 and 5 is recessed for the reception of the opposing teeth of its 5 coöperating member 5 and 3 respectively.

The operating mechanism is spaced from the bolster and rockers, as shown in Fig. 1. Two cylinders 10 and 11, operated by fluid pressure, are pivotally mounted on brackets 10 12, on the underframe, by trunnions 13 which are located just below the body floor and inside of the body sills. The spacing of the latter from each other and from the underframe sills affords ample room between the adjacent body and underframe sills for the positioning of the cylinder and the operation of its piston. The piston rods 14 and 15 are directed downwardly and connect at 16 and 17 respectively with individual levers 18 and 19.

Adjacent levers 18 and 19 and fixedly secured to the underframe sills 2, is a bracket member 20 provided with pin bearing holes 21, 22, 23 and 24 adapted to receive the lever fulcrum pins 25 and 26. The outer end of each lever 18 and 19 is connected to the body by links 27 and 28 pivoted to brackets 29 which are mounted on body sills 6.

If pin 25 be inserted in hole 21, as shown 30 in Fig. 3, and air admitted to cylinder 10, lever 18, operating as a lever of the first class, will be turned on its fulcrum to raise the left hand side of the body as indicated in dot and dash lines in Fig. 3. If, at the same time, pin 26 be inserted in hole 23 and 35 cylinder 11 actuated, lever 19, operating as a lever of the third class, pulls downwardly on the right hand side of the body. With sufficient pressure, either cylinder could 40 dump the car alone provided its piston area was reasonably large. With the cylinders coöperating small pressures and smaller cylinders may be used and the dumping stresses are more evenly distributed. With 45 the restricted space available in railroad car construction, any reduction in the size of equipment is highly advantageous. This is especially true regarding equipment placed beneath the car body as is done in our 50 present car and as would be necessary in a flat car.

It is obvious that if pins 25 and 26 be shifted to holes 22 and 24 respectively, the dumping action of the car will be reversed.

55 The center of gravity of the empty car body and the point of support, or the point of contact between rocker and rocker stand, are coördinated so that the body weight always tends to return the body to upright 60 position. Therefore exhaust of air from the operating cylinders is followed by automatic righting of the body and it is unnecessary to provide mechanism for returning the body to upright position.

65 We do not illustrate the general piping

system of this car as the same does not form part of this invention except as much as is shown in Fig. 3. A supply line 30 has flexible connections 31 to each cylinder and each connection is provided with a cock 32 70 so that its respective cylinder may be cut out of the operating line for repairs or other cause.

By supplying the two cylinders from a single line, the operating fluid has free circulation to both cylinders and will operate as a differential medium to direct the greatest quantity of fluid to the cylinder having the greater piston displacement which, in this construction will be the cylinder on the rising side of the body. It will be understood that the pair of cylinders shown is duplicated near the opposite end of the car and other pairs may be added when necessary.

85

Having described a preferred embodiment of our invention in the above specification, we claim:

1. In a dump car, a tilting body, fluid actuated cylinders operatively connected to opposite sides of said body, each of said cylinders having a single fluid inlet and each adapted to coöperate with the other cylinder or cylinders to tilt said body to either side of the car.

95

2. In a dump car, an under frame including longitudinal sills, and a body tiltingly mounted on said underframe so that all the instantaneous centers of its tilting movement are located below the top of said sills.

100

3. In a dump car, a tilting body, an operating cylinder mounted at one side of said body and connected to that side of said body so as to tilt the body when actuated, a cylinder mounted at the opposite side of said body and similarly adapted to tilt the body, mechanism adapting said cylinders to tilt said body in either direction, and means for supplying fluid pressure to both of said cylinders simultaneously and irrespective of the direction of tilting of said body.

110

4. In a dump car, a body adapted to be tilted to either side, fluid pressure operated cylinders located at opposite sides of said body and adapted to coöperate to tilt said body in either direction, the piston displacement of the cylinder on the rising side of said body being greater than the piston displacement of the cylinder on the lowering side of said body, a single fluid pressure inlet for each of said cylinders, and means for automatically supplying both of said inlets with the required amount of fluid pressure to secure the necessary piston displacement.

120

5. In a dump car, an underframe including longitudinal sills, a body tiltingly mounted on said underframe and provided with longitudinal sills, said body sills being spaced laterally from said underframe sills, and fluid pressure cylinders located in the

125

130

spaces between said body sills and under-frame sills and adapted, when actuated, to tilt said body.

6. In a dump car, truck bolsters, under-frame bolsters mounted thereon and each provided with a rocker stand adjacent the top of said truck bolsters and a tilting car body provided with supporting rockers mounted on said rocker stands.

10 7. In a dump car, an underframe provided with a bolster having a portion of substantial depth between its ends, a rocker stand adjacent its bottom on each side of said portion, a body tiltingly supported on 15 said underframe by means of spaced rockers mounted on said rocker stands.

8. In a dump car, an underframe provided with bolsters spaced longitudinally of the car and having recessed portions between 20 their respective centers and ends, rocker elements mounted in each of said recessed portions, and a body supported on said rocker elements and adapted, by tilting of the latter, to dump its load to the side of the car.

25 9. In a dump car, an underframe, including spaced bolsters and center sills supported upon said bolsters, and a tilting body, including longitudinal sills supported upon said bolsters, a substantial portion of the 30 vertical extent of said underframe sills overlapping with a substantial portion of the vertical extent of said body sills.

10 10. In a dump car, an underframe including longitudinally spaced bolsters and longitudinally extending sills supported thereon, and a tilting body including longitudinal sills supported upon said bolsters, said underframe sills being located between said body sills, and said body sills extending below the tops of said underframe sills.

11. In a dump car, an underframe including longitudinally spaced bolsters and longitudinal sills mounted thereon, and a tilting body including longitudinal sills supported 45 upon said bolsters, the spacing of said underframe sills from each other differing from the spacing of said body sills from each other so that one pair of sills may be located between the other pair of sills and 50 throughout a substantial portion of their length extend between the horizontal planes defining the vertical extent of said other pair of sills.

12. In a dump car; an underframe, a 55 tilting body, a fluid actuated cylinder, a lever operated by said cylinder, pivotally connected to said body, provided with selective means for fulcruming on said underframe at different points and adapted, when 60 fulcrumed at one point and operated, to raise one side of said body and, when fulcrumed at another point and operated, to lower that side of said body.

13. In a dump car, an underframe, a tilting body, operating cylinders mounted on 65

said underframe on opposite sides thereof, individual levers fulcrumed to said under-frame, operated by said cylinders and connected respectively to opposite sides of said body, one lever being fulcrumed so that its 70 operation raises its side of said body and the other lever being fulcrumed so that its operation lowers its side of said body.

14. In a dump car, an underframe, a tilting body, operating cylinders mounted on 75 opposite sides of said underframe and provided with individual levers fulcrumed to said underframe and connected, respectively, to opposite sides of said body, one lever being fulcrumed so that its operation raises its 80 side of said body and the other lever being fulcrumed so that its operation lowers its side of said body and means for changing the fulcruming of said levers so that the operating functions thereof are reversed. 85

15. In a dump car, an underframe, a tilting body supported thereon, an operating cylinder mounted on said underframe and having a piston, a lever pivotally secured to said piston and pivotally secured to said 90 body at a point spaced from the body support and provided with means for being fulcrumed to said underframe at either side of its securing point to said piston so that when said cylinder is actuated the lever will 95 exert an upward or downward thrust, respectively, on that portion of the body to which it is secured.

16. In a dump car, an underframe having longitudinal center sills, a body tiltingly 100 mounted on said underframe, cylinders mounted on said underframe on opposite sides of said center sills and with their piston rods adjacent the lower part thereof, a lever for each cylinder extending from a 105 point adjacent said center sill to a point adjacent the side of said body, and means for fulcruming said lever on the center sill side of said piston or on the opposite side thereof, and a link connecting the end of said lever near the side of said body to said body. 110

17. In a dump car, an underframe including longitudinally spaced bolsters and sills extending between said bolsters, a body tiltingly mounted on said bolsters and provided 115 with longitudinal fish belly sills the ends of which extend over said bolsters and the intermediate portions of which extend below the level of the tops of said underframe sills. 120

18. In a dump car, an underframe, a tilting body, an operating cylinder mounted on one side of said underframe and connected to the adjacent side of said body so as to tilt the body when actuated, a cylinder 125 mounted on the opposite side of said underframe and connected to the adjacent side of said body, and similarly adapted to tilt the body, selective mechanism adapting said cylinders to tilt said body in either direction, 130

- and means for supplying fluid pressure to both of said cylinders simultaneously irrespective of the direction of tilting of said body.
5. 19. In a dump car, an underframe, a body adapted to be tilted to either side to dump its load, fluid pressure cylinders located on opposite sides of said underframe and adapted to coöperate to tilt said body in either 10 direction, the piston displacement of the cylinder on one side of said underframe being greater than the piston displacement of the cylinder on the opposite side of said underframe, a single fluid pressure inlet for each 15 of said cylinders, and means for automatically supplying each of said inlets with sufficient fluid pressure to provide the necessary piston displacement.
20. In a dump car, an underframe having longitudinal sills, a body tiltingly mounted on said underframe and having longitudinal sills and a floor thereon, fluid pressure cylinders mounted on said underframe and positioned between said body sills and outside 25 of said underframe sills and extending from a point adjacent said body floor to a point adjacent the bottom of said underframe sills
- and adapted to tilt the body when operated.
21. In a dump car, an underframe having longitudinal sills, fluid pressure cylinders mounted at each side of said sills and extending above same, a body tiltingly mounted on said underframe and having longitudinal sills extending below the level of the tops of said underframe sills and by the side of said cylinders, and means whereby said cylinders, when actuated, operate to tilt said body.
22. In a dump car, an underframe including spaced bolsters and center sills supported on said bolsters, and a tilting body including longitudinal sills supported upon said bolsters, a substantial portion of the vertical extent of said underframe sills overlapping with a substantial portion of the vertical extent of said body sills throughout a substantial portion of their respective lengths.

In testimony whereof we have hereunto 50 subscribed our names this 10th day of July, 1920.

HOWARD L. BEACH.
WILLARD J. FENDNER.
